UNITED STATES PATENT OFFICE.

HOWARD H. WIXON, OF CHICAGO, ILLINOIS, ASSIGNOR TO STROMBERG MOTOR DEVICES COMPANY, OF CHICAGO, ILLINOIS, A CORPORATION OF ILLINOIS.

DISTRIBUTER FOR IGNITION-DYNAMOS.

1,123,971.

Specification of Letters Patent.

Patented Jan. 5, 1915.

Original application filed March 4, 1910, Serial No. 547,190. Divided and this application filed September 6, 1910. Serial No. 580,718.

To all whom it may concern:

Be it known that I, HOWARD H. WIXON, a citizen of the United States, residing at Chicago, in the county of Cook and State 5 of Illinois, have invented a certain new and useful Improvement in Distributors for Ignition-DYNAMOS, of which the following is a full, clear, concise, and exact description, reference being had to the accompanying 10 drawings, forming a part of this specification.

My invention relates to ignition dynamos such as are employed in connection with gas engines for automobiles.

15 It is directed toward a safety and test arrangement for the high tension circuit and, more specifically, may be associated with distributor mechanism employed when the ignition device is used with a multi- 20 cylinder engine.

This case is divisional from my copending application, Serial No. 547,190, filed March 4, 1910, wherein a magneto ignition device is shown and described. In this type 25 of machine, and in the system employed in connection therewith, inductively related high and low tension circuits are employed and, if the device is to be used in connection with a multi-cylinder engine, it is necessary 30 to distribute the secondary impulses successively among the sparking plugs.

The novel features of my invention lie in the provision of a rotatable spark gap in the secondary circuit in parallel with a 35 spark plug or a plurality of spark plugs, this spark gap constituting not only a safety gap but at the same time performing the function of a testing gap to determine the relation of the moment of sparking with 40 respect to the position of the cylinder piston.

My invention also provides an efficient construction as the physical embodiment of the spark gap arrangement and this and 45 other improvements will be readily understood from the following.

In the accompanying drawings Figure 1 is an end elevational view of the magneto, parts being broken away to show the interior construction; Fig. 2 is a longitudinal sectional view taken on the plane indicated by the line 2, 2 of Fig. 1 and looking in

the direction indicated by the arrows; Fig. 3 is an isolated view similar to the upper part of Fig. 1, further parts being removed 55 to reveal the interior construction; and Fig. 4 is a diagram of the circuit connections.

Like reference characters are applied to the same parts throughout the various figures.

60 The main framework of the machine comprises the non-magnetic base portion 1, a pair of magnetic side portions 2, a non-magnetic top portion 3, and supporting end plates 4 and 5, all held together in some 65 suitable manner, for instance by means of the screws 6, 6. The permanent magnets 7, 7 are in good magnetic contact with the side pieces 2, and, extending upwardly, embrace some of the working parts of the machine, as is usual in the art. In the particular machine herein shown, the space between the magnetic side pieces is occupied by a stationary induction winding 8 comprising the inner or primary coil 9 and the outer 70 or secondary coil 10. Upon the outside of the winding are located the terminals which are intended to engage certain contact members, mounted at certain points on the machine, as will be described subsequently with 75 reference to Fig. 4. Passing axially through the winding are the armature shaft 11 rotatably supported in bearings 12 and 13. The bearing 12 is carried in the supplemental 80 end plate 14, which is secured to the end plate 4 and to the framework of the machine, while the bearing 13 is mounted in the support 15 held in the other end plate 5. Antifriction rollers 16, 16 work in the bearings 12 and 13, as is clearly shown in the 85 drawings. A pair of segmental polar extensions 17 and 18 are secured to the armature shaft at opposite ends of the winding, first by means of the screw threads on the armature shaft and second by means of the set 90 screws 19, 19. The polar extensions as well as the armature shaft—at least that portion of the armature shaft which is included between the polar extensions—are of magnetic material, and it will be seen, therefore, 95 that the armature shaft constitutes a rotatable magnetic core for the stationary induction winding. The angular position of the polar extensions 17 and 18 on the arma-

60

100

ture shaft is such that they lie substantially diametrically opposite, as indicated in Fig. 2, and in order to provide a large surface on the faces of these polar extensions I have 5 preferably formed the extensions with elongations 20, 20 projecting into the space between the winding and the framework. It will appear to those skilled in the art that as the armature is rotated or oscillated the 10 magnetic flux of the field will be periodically short-circuited through the winding, first in one direction and then in the reverse direction, and that this will set up an electro-motive force in the winding by the action 15 of the field magnet. If the primary coil is short-circuited, the current flowing therethrough generates lines of magnetic force which largely neutralize the existing magnetic field—that is, they force back or oppose a change of magnetism through the 20 coil. As soon as the circuit in the primary winding is broken, the counteraction of the generated opposing flux ceases. Owing to the change which thereby instantaneously 25 arises in the number of lines of force passing through the secondary coil from the field magnets, the potential rises so high in the secondary coil that a spark is produced across the contacts of the spark plug to 30 ignite the explosive mixture in the engine cylinder. The wire in the primary coil is comparatively coarse and comprises comparatively few turns, while the wire comprising the secondary coil is comparatively 35 fine and comprises a comparatively large number of turns, in order that the electro-motive force generated in the secondary coil may be sufficiently high to cause sparking at the spark plugs of the engine cylinder.

40 The armature shaft 11 has an extension 21 to which is rigidly secured the yoke 22, having at its opposite ends a pair of rollers 23 and 24. These rollers are insulated from the yoke, as clearly shown in Fig. 1. The 45 yoke 22 constitutes the movable contact member of the interrupter, the function of which will be referred to when Fig. 4 is taken up for description, and which is shown and described in detail in my copending application, Serial No. 580,717, filed of even date herewith. Suffice it in this description to say that the rollers 23 and 24 coöperate with movable contact springs 25 and 26, associated with stationary contacts (not 55 shown), to break the primary circuit periodically, the pairs of contacts being arranged in parallel and one of the contacts being arranged to open before the other, all as will be described with reference to Fig. 4.

60 Coming now to the auxiliary spark gap arrangement of my invention, it will be seen that, for the sake of illustration, it has been assumed that the precise embodiment 65 of my magneto generator illustrated in the drawings is for a four-cylinder engine and,

therefore, the distributor is shown as provided with four spring contacts 27, 28, 29 and 30 mounted in the insulating ring 31. Each contact is electrically connected with a contact terminal 32 by means of a conductor 33. From the terminals 32 connections lead to the spark plugs of the engine cylinders. Insulating thimbles 33' protect the upper portions of the contact terminals 32. The supporting ring 31 and the contact terminals 32 are carried by a base plate 34 of insulating material. A correspondingly shaped cover plate 35, also of insulating material, is arranged to fit over the base plate 34, as indicated in Fig. 2, to inclose the plates and thereby protect them from liability to injury. Screws 36, passing through openings 37 in the base and cover-plates, secure what may be termed the stationary part of the distributor to the end plate 5. Within the cylindrical space 38, formed by the ring 31, moves the annular member 39 of insulating material. A glass or mica plate 40 carried by the cover 35 is provided in front of the cylindrical space 38. The member 39 has fixedly mounted thereon the metallic arm 41, which terminates at its outer end in an arc-shaped engaging surface 42, forming part of the periphery 43 of the annular member 39, as best shown in Fig. 3. At its inner end the metallic arm 41 is in electrical contact with the extension 44 of the shaft 45. It is to this extension 44 that the annular member 39 is suitably secured, as by screw-threaded engagement. An insulating bushing 46 is fixed upon the member 39 by having its shank portion 47 inserted in and opening in the annular member, as best shown in Figs. 2 and 3. The front portion of the bushing 46 serves to cover up the arm 41. This bushing carries the spark electrode 48, whose shank portion 49 has electric contact with the metal disk 50 which is preferably fixed to the insulating member 39. The projection 51 on the extension 44 coöperates with the electrode 48 to form a spark gap. I will subsequently explain how this spark gap forms a combined safety and testing spark gap. The shaft 45 is in reality a part of the auxiliary shaft 52, mounted in bearings 53 and 54, set in the end plates 4 and 5, respectively, antifriction balls 55, 55 being provided in each instance. This auxiliary shaft carries the gear 56, incased between the end plate 4 and the supplementary end plate 14, and this gear meshes with the pinion 57 secured upon the main shaft 11, the gear ratio being such that the pinion 57 makes two revolutions to every revolution of the gear 56. The part 45 is insulated from the main portion of the auxiliary shaft 52 by means of the insulating portion 58, but is connected with one of the terminals of the secondary winding by means of the 130

spring-pressed buttons 59 and 60, the spring 61, the contact ring 62, and the pin 63. It is to be noted in this connection that the otherwise insulated electrode 48 is grounded to the machine by means of the disk 50 and the shell 64 which forms part of the shaft and which is associated directly with the bearing. It is now apparent that when the arm 41 is in contact with any one of the four spring contacts 27, 28, 29 and 30, the spark gap will be in parallel with the contacts of the connected spark plug.

The various parts which have been described more or less broadly, as well as those which have been described in detail, are all so interconnected and insulated and so associated with the windings 9 and 10 that the circuit arrangement of Fig. 4 may be maintained. Referring to this figure, it will be seen that the primary winding 9 is connected between ground G and the movable contacts of the interrupter, while the stationary contacts of the interrupter are connected back to ground. It will also be noted that a condenser 65, conveniently located over the part 3 within the horseshoe magnets (Fig. 2), is connected in parallel with the interrupter, the object of this being, as is well known in the art, to prevent as much as possible the sparking at the electrodes which interrupt the primary circuit and also to increase the voltage in the secondary circuit by accelerating the flux variations through the induction winding. It will also be noted that the secondary winding is connected between ground and the movable member of the distributor, while the stationary contacts of the distributor are connected through the spark plugs back to ground.

I have previously stated that the electrodes 48 and 51 constitute a combined safety and testing gap. How they constitute a safety gap is apparent from the fact that these electrodes are in parallel with the spark plugs, so that if for any reason the current should fail to leap across the electrodes of the spark plug which the distributor has connected in the circuit of the secondary winding, the secondary current surging through the secondary circuit under high pressure would leap across the spark gap formed by the terminals 48 and 51, thus discharging the secondary circuit to ground safety. Otherwise, there would be danger of the secondary voltage driving the current through the insulation of the induction winding.

The testing feature of the spark gap formed by the electrodes 48 and 51 is brought about by the fact that the spark gap rotates in unison with the distributor arm and in alignment therewith, so that by disconnecting a cylinder spark plug from the distributor and operating the magneto,

the position of the spark that will pass across the electrodes 48 and 51 will indicate at what position of the engine piston the moment of sparking is occurring. If the sparking is too early or too late the interrupter may be readily adjusted to meet the requirements. Of course it is obvious that this rotatable testing gap does not depend for its advantage and utility upon the other features of my invention, and I therefore claim the same broadly.

Having thus described my invention, what I claim as new and desire to secure by Letters Patent is:

1. A distributor for magneto generators comprising, in combination, a plurality of stationary contacts adapted to be connected to the sparking electrodes of the engine cylinders, a rotatable contact member for successively closing the circuit through said stationary contacts, and a pair of auxiliary contacts moving in unison with said member to provide a safety and testing gap, one of said auxiliary contacts being electrically connected with said current member while the other auxiliary contact is insulated therefrom, the gap between said auxiliary contacts being adapted to be connected in parallel with said sparking electrodes.

2. A distributor for magneto generators comprising, in combination, a plurality of stationary contacts adapted to be connected to sparking electrodes of the engine cylinders, a rotatable contact member for successively closing the circuit through said stationary contacts, an insulating disk for supporting said member, and a pair of auxiliary contacts mounted on said disk in radial alignment with said contact member to provide a safety and testing gap rotatable with the contact member, said safety and testing gap being adapted to be connected in parallel with or in substitution of one of the sparking gaps.

3. In combination, a source of alternating current, means for interrupting said current, a plurality of contacts, jump spark terminals between each of said contacts and ground, a rotatable contact maker for connecting any of said contacts with said source of current, and a terminal piece forming a gap with said contact maker, said piece being grounded.

4. In combination, an insulated stationary grounded contact, a rotatable member carrying an insulated metallic part for engagement with said contact, an electrode carried by said metallic part for engagement with said contact, an electrode carried by said metallic part, and an associated electrode carried with but insulated from said metallic part, said last-named electrode being associated with said first-named electrode to form a spark gap and being grounded.

5. A magneto generator for ignition purposes provided with a pair of rotatable contacts to form a testing gap in combination with a sparking circuit having a fixed spark gap in parallel with said rotatable sparking gap.

In witness whereof, I hereunto subscribe

my name this 3rd day of September A. D.
1910.

HOWARD H. WIXON.
